SAFETY RAZOR

Alexander Galbraith, Dalmuir, Scotland

Application September 9, 1936, Serial No. 99,909
In Great Britain October 2, 1934

5 Claims. (Cl. 30—71)

This invention relates to safety razors, and has for its primary object to provide a safety razor in which the blade may have a resilience comparable with that of the blade of a hollow ground razor.

As is understood, safety razor blades are usually clamped more or less rigidly with considerable deformation between guard and end cap elements, thus producing a heavy or inert 10 feeling in the use of the razor. In effect, there is probably no existing safety razor which has the resilience, tang and clean-cutting action experienced with the use of a high quality hollow-ground razor.

15 For a safety razor to give the same satisfaction as a hollow ground razor at its highest point of efficiency, the blade must be afforded considerable freedom, i. e., the blade must be so mounted that it has freedom to flex transversely of its plane in at least the direction away from the 20 guard element. A safety razor blade answering these conditions will retain its efficiency much longer than the usual safety razor blade. Accordingly, over any given period, renewals are 25 less and economy results, apart from the fact that all the qualities of a high class hollow-ground razor are at the disposal of the user, without sacrifice of the safety properties.

These requirements are fulfilled by the present 30 invention, which provides a safety razor having a flexible blade adapted to be accommodated between a guard element and a cap element in such wise that the blade is free of restraint by the cap element for at least the greater 35 part of its length or breadth, the blade having freedom to flex transversely of its plane in at least the direction away from the guard element, within the space between said elements.

When the blade is held at one end the blade 40 is free to flex cantilever fashion. With the blade held at one or more selected points resilience may be distributed over the blade as desired. Again, the blade may be held locally with a sliding grip permitting the blade not only to 45 flex transversely of its plane but to perform limited sliding movements in its own plane. Further, in the latter case, the blade may be free also to perform angular and/or orbital movements in its own plane.

50 Adjustable blade-engaging or movement-restraining means may be so arranged and distributed as to give any desired resilience to the blade.

In addition, where the blade is restrained at 55 one or more points, variations in resilience, from

the point or points where the blade is secured, may be obtained by making provision for increasing or decreasing, at will, the distance from the cutting edge or each cutting edge of the blade to the adjacent edge or edges of the end 5 cap.

In a practical construction, according to the invention, there may be provided, inter alia,

(a) a variable amount of adjustment between the guard and end cap elements, while, at the same time, the greater part of the blade is free to flex transversely of its plane between the said elements;

(b) means for adjusting the freedom afforded to the blade to flex transversely of its plane, said 15 means permitting the blade to be gripped cantilever fashion at either end, or to be gripped locally at a point or points shiftable to distribute the permissible resilience, with a positive grip or a sliding grip;

(c) means for adjusting the extent of the cutting edge or each cutting edge of the razor blade behind the guard and/or end cap elements.

The blade may be held positively or with a sliding grip at one end, and while so held may 25 yet have some degree of freedom at that end, between the guard and end cap elements, and the permissible floating movement of the blade between the said elements greater at the other end.

Again, the blade may be held at two points 30 on the same side of a median line parallel to the edges of the blade, corresponding to two of the points indicated above, and again may have such degree of freedom as is permitted by the spacing of the guard and end cap elements.

Again, the blade may be held only at a point 35 located centrally of the blade, or in intermediate positions, between the centre and either end, with adjustable floating movement at either end, as before.

The blade movements described may be obtained singly or in combination as desired by the user, it being understood that any one setting of the blade may suit a particular strength 45 of beard and that strong beards will require less give or resilience of blade than soft beards.

The invention is illustrated in the accompanying drawing in which Figs. 1 and 2 are a vertical section and a plan view, respectively, showing, 50 by way of example only, a practical construction of a safety razor head. Fig. 3 is a side elevation showing the razor head connected to a handle.

In the construction shown the cap 6 is adjust- 55

ably connected to the guard 2 by a screw 7 penetrating the guard 2, the cap 6 being tiltable on the ball head of the screw 7 so that it may be adjusted universally relatively to the guard 2. A spaced pair of micrometer screws 8, 9 threaded upwardly through bosses 10 on the guard 2 present at their upper ends pintles 11, 12 engaging arcuate slots 13, 14 in the cap 6, the slots 13, 14 being concentric with the screw 7, so that the cap 6 may be adjusted angularly about the axis of the screw 7. The screws 7, 8 and 9 penetrate a slot 15 in the blade 3, the screws 8, 9 presenting collars 16, 17 where they penetrate the slot 15. The screws 8, 9 are formed beyond the collars with laterally projecting tongues 18, 19 engageable selectively with the blade 3 or with the cap 6.

The handle may be in the form of an internally threaded tube fitted to the free end portion of the screw 7.

By suitable adjustment of the screw 8 the blade 3 may be nipped against the guard 2 by the tongue 18 while the screw 9 may be adjusted, with the tongue 19 bearing against the inner face of the cap 6 to vary the range through which the blade is free to flex.

The angular setting of the tongues 18, 19 also affects the resiliency of the blade by virtue of the eccentricity of the tongues 18, 19.

The blade may be so lightly held that it is free to slide in its own plane.

It will be obvious from the foregoing that there exists a wide variety of settings and adjustments for the blade, in all of which the blade is free to flex in the direction away from the guard 2.

It will be seen that the tongues 18, 19 are engageable selectively with the underside of the cap 6 whereby to exercise control of the position of the cap 6 relatively to the guard 2, the cap 6 being pulled towards the guard 2 by the screw 7. Manifestly, the blade may be gripped at one end or the other between the guard and the cap which are maintained in spaced relation at the free end of the blade by the tongue adjacent thereto.

Manifestly, the blade may be gripped at or near or along one longitudinal edge, so that it may be tilted out of its plane to a variable angle widthwise between the guard and end cap elements. A handle 20 may be secured to the razor head by screwing it onto the projecting end of the screw 7, as shown in Fig. 3.

I claim:—

1. In a safety razor, in combination, a guard, a cap, means for spacing the guard from the cap throughout at least a portion of the length thereof, said space being greater than the thickness of a blade to be positioned between said guard and cap, a blade between said guard and cap, said blade having a portion extending into said space

and free to move toward and away from said guard, and means for fixing a portion of the blade longitudinally of said free portion against movement toward and away from the guard.

2. In a safety razor, in combination, guard and cap elements, means for maintaining said guard and cap elements at least partially spaced apart a distance greater than the thickness of a blade to be accommodated between said elements, a flexible apertured blade accommodated between said elements, means penetrating said blade and adjustably connecting said elements for permitting relative angular adjustment of said elements and means engaging said blade at selectable points to maintain a part thereof fixed against movement toward and away from said elements and for controlling the freedom of another part of the blade to flex within the space between said elements.

3. In a safety razor, in combination, guard and cap elements, a flexible slotted blade accommodated between said elements, a screw penetrating the slot in said blade and connecting said elements, spaced screws adjustably fitted to one of said elements and engaging the other of said elements with freedom, said spaced screws penetrating the slot in said blade, and tongues projecting laterally from said last mentioned screws for controlling the position of the blade.

4. In a safety razor, in combination, guard and cap elements, means for maintaining said guard and cap elements at least partially spaced apart a distance greater than the thickness of a blade to be accommodated between said elements, a flexible apertured blade accommodated between said elements, means penetrating said blade and adjustably connecting said elements for permitting relative angular adjustment of said elements, and means engageable with said blade at selectable points between its ends to maintain a part thereof fixed against movement toward and away from said elements and for controlling the freedom of another part of the blade to flex within the space between said elements.

5. In a safety razor, in combination, guard and cap elements, a flexible apertured blade accommodated between said elements, a screw penetrating said blade and adjustably connecting said elements for permitting relative angular adjustment of said elements, and means engageable with one face of said blade and with the adjacent face of one of said elements, said means being adjustable to vary the point of engagement with said blade and to vary a dihedral angle contained between said elements by movement of the portion of the element engaged thereby with respect to the other element to a greater extent than the remaining portion thereof.

ALEXANDER GALBRAITH.
